MERCHANDISE DISPLAY RACK

Filed March 12, 1945

UNITED STATES PATENT OFFICE

2,500,115

MERCHANTISE DISPLAY RACK

Leslie H. Burlin, Valparaiso, Ind., assignor to
 Milton L. Sturm, doing business as Milton
 Sturm & Company, Chicago, Ill.

Application March 12, 1945, Serial No. 582,384

5 Claims. (Cl. 211—70)

1

This invention relates to merchandise display racks.

It is one of the objects of the present invention to provide a display rack for receiving and holding individual articles of merchandise of similar shapes and which will display a maximum amount of the outer area of each article.

It is a further object of the present invention to provide a display rack which is rotatably mounted so that it may be turned to bring the different articles of merchandise displayed thereon into a position desirable to facilitate the making of a selection for a particular piece of merchandise on the display rack.

Consider a rack for holding and displaying a plurality of objects, such as, for instance, tooth brushes. The rack is adapted to hold tooth brushes of various kinds and various colors. Each tooth brush may be labeled. It is desirable that all of the brushes shall be so held in the rack that a customer can very quickly examine all of them to make a desired selection. It is one of the objects of the present invention to provide a display rack in which individual articles such as, for instance, tooth brushes, may be mounted by merely dropping the brush into a specific position in the rack and may be removed from the rack by merely lifting the brush therefrom.

It is a further object of the present invention to provide such a display rack in which the brushes are held in a neat and substantially parallel arrangement with a maximum number of brushes visible from the outer periphery of the rack as the rack is turned.

It is a still further object of the present invention to provide a display rack with a central column for receiving and holding a display sign which remains stationary even though the merchandise-holding portion of the rack is being rotated to bring the merchandise in different parts of the rack to the foremost position. It is a still further object of the present invention to provide a rotatable display rack wherein substantially all of the merchandise held on the rack is visible at all times regardless of the position of the rack.

The attainment of the above and further objects of the present invention will be apparent from the following specification taken in conjunction with the accompanying drawings forming a part thereof.

In the drawings:

Figure 1 is a longitudinal sectional view through a display rack embodying the present invention;

Figure 2 is a plan view of the display rack taken

at right angles to the longitudinal axis of the central supporting column; and

Figure 3 is a fragmentary sectional view taken along the line 3—3 of Figure 1.

Reference may now be had more particularly to the drawings wherein like reference numerals designate like parts throughout.

The rack is indicated by the reference numeral 1 and comprises a base 2 which has a flat bottom 3 of a generally oval shape and which is wedge-shaped in thickness and has an inclined top 4 which is also oval-shaped. The top 4 is at an angle of approximately 15° to the horizontal. A circular wooden rod or column 6 extends into a hole in the base 2, being press fitted thereinto so that the center column is rigidly united with the base. The longitudinal axis of the column 6 is inclined approximately 15° to the vertical or 75° to the bottom surface 3 of the base 2. A circular wooden spool 7 having flat upper and lower surfaces is slipped over the top of the column 6 and rests on the surface 4 of the base 2.

An article supporting frame, which is the principal part of the rack, is indicated at 10. The frame consists of a circular base 11 made of plywood or the like, which is overlaid by a circular stencil 13 of the same outside diameter as that of the base. A band 14 surrounds the periphery of the base and the stencil, thereby concealing the joint between the two. A wooden circular spool 17, which is flat at the top and flat at the bottom, rests on the stencil 13. Two or more nails 18—18 extend through the base 11, the stencil 13, and into the bottom of the spool 17 and thus serve to

hold the base, the stencil and the spool together. The bottom of the base 11 may be counterbored for receiving the heads of the nails or, if not counterbored, then the nails are driven so firmly in place that the heads thereof barely, if at all, project from the bottom of the base. Another circular stencil 20, which is preferably made of a sheet of transparent plastic material, is nailed to the top of the spool 17 as by two or more nails 21—21 that extend through the stencil 20 and into the spool 17. The stencil 20 is appreciably thinner than the stencil 13 and is of the same diameter as the stencil 13. The two stencils have identical cuts therein, of which more will be said as this description proceeds.

In order to support the upper stencil at its periphery the base 12 and each of the two stencils are provided with a plurality of holes, in this instance six, uniformly spaced from one another and adjacent the periphery of the base and the stencils. Through each of these holes there ex-

2

tends a rod 25 which is surrounded by a sleeve 26 that is relatively loose on the rod. The bottom of each rod 25 is press fitted into its receiving hole in the base 11. Each sleeve 25 rests on the stencil 13 and is held in position by its rod 25 and supports the top stencil 28 adjacent the periphery of the top stencil. The article-supporting frame is slipped over the column 6 until the base 11 rests on the spool 7. The central bore through the base 11, the spool 17, and the two stencils 13 and 20 are in alignment and are only slightly in excess of the diameter of the column 6 so as to permit free sliding and turning of the article-supporting frame 10 on the column 6. After the frame has been positioned on the column another circular spool 28 having a flat top and a flat bottom is also slipped over the column 6 and serves to conceal the tops of the nails 21. A nail 29 is driven through the spool 28 into the column 6 to secure the spool 28. Thereafter a knob 30, which is circular in cross section and has a central bore extending part way therethrough from the bottom thereof, is slipped over the top of the column 6. The knob makes a tight friction fit with the column and is thus held in place. The knob 30 has a straight slot 33 extending across the top thereof. This slot is provided for receiving an advertising sign or placard such as is indicated at 34.

The article-supporting frame 10 is adapted to support a large number of identical or similar articles and display them to maximum advantage. To that effect each of the stencils 13 and 20 has a number of oval holes 40 therein. The holes in the two stencils are in alignment when viewed in a direction parallel to the longitudinal axis of the column 6, that is, along a line at right angles to the plane of the base 11. In this instance the holes 40 are arranged in three circular rows. In the inner row 41 the oval holes are arranged with their longitudinal or major axes substantially at right angles to a radius extending from the center of the oval holes 40 to the center of the column 6. In the middle row 43 the holes 40 are arranged so that their major axes extend substantially radially of the stencil. In the outer row the holes 40 are arranged with their major axes at an angle approximately 35° to a radius drawn from the center of the stencil to the center of the major axis of the hole. The holes 40 are made of an oval shape so that the supporting frame may receive in each pair of aligned holes of the stencils an article such as a case 50 which is transparent and contains a tooth brush. One standard sectional shape of such cases 50 is an oval shape corresponding to the shape of a hole 40 in the stencils. The case 50 extends through the hole in the top stencil. The bottom of the case enters into a corresponding hole in the stencil 13, thus holding the case 50 in proper position for display. By reason of the fact that the holes 40 in the outer row of holes are at an angle to the radius, a large part of the surface of each case 50 at the front of the display rack is visible, while at the same time allowing for a large number of article-receiving holes 40 in the outer row of holes. By turning the frame 10 about the center of the column 6 as an axis different parts of the frame are brought to a forward position to facilitate examination of adjacent articles on the frame.

In compliance with the requirements of the patent statutes I have here shown and described a preferred embodiment of my invention. It is, however, to be understood that the invention is

not limited to the precise construction here shown, the same being merely illustrative of the principles of the invention. What is considered new and desired to be secured by Letters Patent is:

1. A display rack comprising a base, an inclined column secured to and extending upwardly therefrom, a spool surrounding the column above the base, an article supporting frame through the center of which the column extends, said frame resting on said spool and being rotatable about said column, said frame including a bottom member, a bottom stencil on the top surface of the bottom member, a top stencil spaced from and of the same shape as the bottom stencil, and means for securing the bottom member and the two stencils together, means secured to the column and overlying the top stencil thereby holding the frame against upward removal from said column, each of said stencils having a plurality of holes therethrough arranged in a plurality of concentric circles centered at the center of the column, the holes in the two stencils being in alignment to receive and hold articles, and a knob at the top of the column.

2. A display rack comprising a base, an inclined column secured to and extending upwardly therefrom, a spool surrounding the column above the base, an article-supporting frame through the center of which the column extends, said frame resting on said spool and being rotatable about said column, said frame including a bottom member, a bottom stencil on the top surface of the bottom member, a second spool on the stencil with its longitudinal axis at right angles to and passing through the center of the bottom member, means securing the bottom member, the stencil and the second spool together, a top stencil of the same shape as the bottom stencil and centrally supported by said second spool, means for supporting the periphery of the top stencil in fixed spaced relationship to the bottom member, means secured to the column and overlying the top stencil thereby holding the frame against upward removal from said column, each of said stencils having a plurality of holes therethrough arranged in a plurality of concentric circles centered at the center of the column, the holes in the two stencils being in alignment to receive and hold articles.

3. A display rack comprising a base, an inclined column secured to and extending upwardly therefrom, a spool surrounding the column above the base, an article-supporting frame through the center of which the column extends, said frame resting on said spool and being rotatable about said column, said frame including a circular bottom member, a circular bottom stencil on the top surface of the bottom member, a second spool on the stencil with its longitudinal axis at right angles to and passing through the center of the bottom member, means securing the bottom member, the stencil and the second spool together, a top stencil of the same shape as the bottom stencil and centrally supported by said second spool, means for supporting the periphery of the top stencil in fixed spaced relationship to the bottom member, said means comprising headed pins extending through the top stencil and secured in said bottom member and collars surrounding the pins and extending from the bottom stencil to the top stencil, means secured to the column and overlying the top stencil thereby holding the frame against upward removal from said column, each of said stencils having a plurality of oval holes therethrough ar-

ranged in a plurality of concentric circles centered at the center of the column, the holes in the two stencils being in alignment to receive and hold articles.

4. A tooth brush display rack comprising a base, an inclined column secured to and extending upwardly therefrom, a spool surrounding the column above the base, an article-supporting frame through the center of which the column extends, said frame resting on said spool and being rotatable about said column, said frame including a circular bottom member, a circular bottom stencil on the top surface of the bottom member, a second spool on the stencil with its longitudinal axis at right angles to and passing through the center of the bottom member, means securing the bottom member, the stencil and the second spool together, a top stencil of the same shape as the bottom stencil and centrally supported by said second spool, means for supporting the periphery of the top stencil in fixed spaced relationship to the bottom member, said means comprising headed pins extending through the top stencil and secured in said bottom member and collars surrounding the pins and extending from the bottom stencil to the top stencil, and a collar surrounding and secured to the column and overlying the top stencil thereby holding the frame against upward removal from said column, each of said stencils having a plurality of oval holes therethrough arranged in a plurality of concentric circles centered at the center of the column, the holes in the two stencils being in alignment, the respective holes being adapted to receive and display oval-shaped tooth brush packages, the major axis of each hole in the outer circle being at a substantial acute angle to a radius from the center of the hole to the center of the column, the major axis of each

hole of the innermost row being at right angles to such radius, the major axis of each opening in an intermediate row being radial.

5. A display rack comprising a base, an inclined column secured to and extending upwardly therefrom, an article supporting frame through the center of which the column extends, said frame including a bottom member, a bottom stencil on the top surface of the bottom member, a top stencil spaced from and of the same shape as the bottom stencil, and means for securing the bottom member and the two stencils together, means secured to the column and overlying the top stencil thereby holding the frame against upward removal from said column, each of said stencils having a plurality of holes therethrough arranged in a plurality of concentric circles centered at the center of the column, the holes in the two stencils being in alignment to receive and hold articles.
